C. A. GARVEY.
FOUNTAIN BRUSH.
APPLICATION FILED APR. 21, 1919.

Patented Oct. 7, 1919.

UNITED STATES PATENT OFFICE.

CHRISTOPHER A. GARVEY, OF CLAYTON, MISSOURI.

FOUNTAIN-BRUSH.

1,318,066.

Specification of Letters Patent.

Patented Oct. 7, 1919.

Application filed April 21, 1919. Serial No. 291,773.

To all whom it may concern:

Be it known that I, CHRISTOPHER A. GARVEY, a citizen of the United States of America, a resident of Clayton, in the county of St. Louis, State of Missouri, have invented certain new and useful Improvements in Fountain-Brushes, of which the following is a full, clear, and exact description, reference being had to the accompanying drawings, forming a part of this specification.

My invention relates to an improvement in fountain brushes or marking devices, and pertains particularly to means for controlling the flow of liquid from the reservoir of a device of this kind. The object of the present invention is to provide a valve at the outlet from the reservoir adapted to open in response to movement of the device when in use, and means coöperable with said valve operable in response to use of the device adapted to hold it in closed position when the device is not being operated, although held idly in the hand in different positions.

Figure I is an elevation of my device illustrated in the form of a stencil brush.

Fig. II is a longitudinal section, partly in elevation.

Fig. III is a view, partly in elevation and partly in longitudinal section, including the brush tip and the lower end of the reservoir, in inclined position to illustrate the positions assumed by the valve and the valve controlling device when the brush is merely tilted to one side.

Fig. IV is a cross section taken on line IV—IV, Fig. II.

Fig. V is a cross section taken on line V—V, Fig. II.

In the drawings, I have shown my device in the form of a fountain brush suitable for stenciling or other purposes wherein a brush tip is required and will describe the device as of this form. It will, however, be understood that any other desirable form of marking tip might be utilized in lieu of that shown.

A designates the reservoir of my fountain brush which is intended to serve also as a handle by which the marking device is manipulated. At the lower end of the reservoir is a discharge device B containing a cavity b and to which the tip C is secured. In the discharge device, above the cavity b is a valve pocket 1, at the bottom

of which is a valve seat member 2 provided with a discharge orifice 3 providing communication between the valve pocket 1 and the cavity b. The valve pocket 1 communicates with the interior of the reservoir A, as will be hereinafter fully explained.

4 designates a valve head resting on the valve seat member 2 and having a pendant or pendulum stem 5 extending through the aperture 3 in the valve seat member and into the cavity b. The valve stem 5 is adapted to vibrate in said cavity b when the brush is moved to and fro and by vibrating acts to tilt the valve head 4 on the valve seat member 2 with an intermittent motion which will permit flow of liquid past the valve head from the valve pocket to the cavity b each time the valve is opened by the tilting motion.

In the upper end of the valve pocket 1 is a centrally apertured disk 6, the aperture in said disk being in alinement with the discharge orifice 3 in the valve seat member 2.

E designates a valve controlling device 80 by which the tilting of the valve head 4 on the valve seat is governed. This valve controlling device comprises a head 7 located in the valve pocket 1 against the valve head 4, and a stem 8 extending upwardly from said head 7 through the apertured disk 6 and into the reservoir A, the stem preferably terminating in a weighted upper end 9. The head 7 of the controlling device is preferably notched at its periphery to permit a ready flow of liquid past said head in the valve pocket.

In the practical use of my fountain brush it is manipulated by grasping the reservoir A and using it as a handle as usual and the brush is moved first in one direction and then in an opposite as a natural consequence of its use. During the repeated movements of the device in one direction and then in the opposite direction the valve controlling device E tilts backwardly and forwardly, and each time that it tilts the valve head 4 is permitted to tilt under the influence of the stem 5 depending therefrom. The result is a succession of valve unseating operations while the brush is being wielded and an intermittent flow of liquid from the reservoir to the cavity b and therefrom to the tip C.

It will be understood from the foregoing 110 that the valve controlling device E operates in a manner to permit the operation of the

valve controlling the discharge orifice 3 in the valve seat member. However, if the marking device is held in the hand without movement, even though in an inclined position as seen in Fig. III, the valve controlling device will, by pressure against the valve head, retain said valve against the seat member and prevent escape of liquid through the discharge orifice as would occur in the absence of the valve controlling device E.

The apertured disk 6 preferably has screw threaded engagement with the wall of the valve pocket 1 thereby providing for the adjustment of this disk relative to the head of the valve controlling device E in order that the degree of tilting movement of said device may be regulated with consequent regulation of the degree to which the valve may open.

20 I claim:

1. A device of the character described comprising a reservoir, a valve seat member having a discharge orifice for the escape of the contents of said reservoir, a valve controlling said orifice tiltably in response to to and fro movements of the device, and a second independently tiltable means co-acting with said valve whereby its tilting movement is controlled.

30 2. A device of the character described comprising a reservoir, a valve seat member having a discharge orifice permitting escape of liquid from said reservoir, a valve controlling said orifice tiltably in response to to and fro movements of the device, and an independently tiltable valve controlling member above said valve operable in response to tilting of said reservoir.

3. A device of the character described comprising a reservoir, a valve seat member having a discharge orifice permitting the escape of liquid from said reservoir, a valve resting on said valve seat member tiltably in response to to and fro movements of the device, and an independently tiltable valve

controlling member comprising a head contacting with said valve and a stem carried by said head.

4. A device of the character described comprising a reservoir, a valve seat member having a discharge orifice permitting escape of liquid from said reservoir, a valve tiltably on said valve seat member in response to to and fro movements of the device, an independent valve controlling member tiltably in response to to and fro movements of the device, and adjustable means for limiting the tilting movement of said controlling member.

5. A device of the character described comprising a reservoir, a valve seat member having a discharge orifice permitting escape of liquid from said reservoir, a valve head resting on said valve seat member and having a stem depending therefrom, and an independent valve controlling device tiltably arranged above said valve head, said valve controlling device including a head in contact with said valve head and a stem extending upwardly from said head.

6. A device of the character described comprising a reservoir, a valve seat member having a discharge orifice permitting escape of liquid from said reservoir, a valve head resting on said valve seat member and having a stem depending therefrom through said orifice, and an independent valve controlling device tiltably arranged above said valve head, said controlling device comprising a head loosely fitted to said valve head and a stem extending upwardly from said head, and an apertured screw disk above said valve seat member through which the stem of said controlling device extends and by which the tilting movement of said controlling device is regulated.

In testimony that I claim the foregoing I hereunto affix my signature.

CHRISTOPHER A. GARVEY.
